DRILL OILER

John Herman Lind, Santa Barbara, Mexico

Application December 1, 1934, Serial No. 755,619

4 Claims. (Cl. 184—55)

The device forming the subject matter of this application is an oiler, and the invention aims to provide an oiler which is adapted to be assembled with any standard rock drill or the like, to replace the common line oiler, or multiple oiler, used at present. The invention aims, further, to provide novel means for securing a flow of oil from the oiler to the rock drill which is to be oiled, the flow of oil being governed by the pressure within 10 the drill, as the automatic valve of the drill opens and closes.

It is within the province of the disclosure to improve generally and to enhance the utility of devices of that type to which the invention appertains.

With the above and other objects in view, which will appear as the description proceeds, the invention resides in the combination and arrangement of parts and in the details of construction 20 hereinafter described and claimed, it being understood that changes in the precise embodiment of the invention herein disclosed, may be made within the scope of what is claimed, without departing from the spirit of the invention.

25 In the accompanying drawing:

Fig. 1 shows, in side elevation, a portion of a rock drill wherewith the device forming the subject matter of this application has been assembled;

30 Fig. 2 is a longitudinal section of the oiler;

Fig. 3 is a cross section on the line 3—3 of Fig. 2;

Fig. 4 is a cross section on the line 4—4 of Fig. 2.

35 The oiler forming the subject matter of this application comprises a cylindrical body 1, provided at one extremity with an end wall 6, there being a concaved recess 30 on the inner side of the end wall. A reduced neck 2 projects outwardly from the end wall 6. A plug 3 is threaded into the neck 2 and is provided with a cavity 4, which increases the capacity of the body 1. The cavity 4 has a flared mouth 5, communicating with the recess 30. The inner end of the plug 3 is flush 40 with the wall of the recess 30. The plug 3 is provided with an outstanding flange 7 which abuts against the end of the neck 2. The plug 3 is provided with an extension 8, having an opening 9, the opening 9 being adapted to receive a tool, used 45 for threading the plug to place, as shown in Fig. 2.

The numeral 10 designates a foot, which is threaded into the end of the body 1 which is opposite to the neck 2. The foot 10 has a flange 11 50 which abuts against the end of the body 1. Out-

wardly of the flange 11, the foot 10 is supplied with a wrench head 12, whereby the foot can be threaded conveniently into the body 1. A reduced, tapered, threaded neck 14 projects outwardly from the wrench head 12. In the outer end of the foot 10, and, specifically, in the outer end of the neck 14, there is a concaved recess 15. The foot 10 has a central, inwardly extended projection 16, and about the projection 16 there is a circumscribing channel 17, which increases the 10 capacity of the body or reservoir 1. The projection 16 has a threaded bore 18. At the end of the threaded bore 18, there is a tapered chamber 19, located in the projection 16 of the foot 10. A reduced passage 20 leads from the chamber 19 15 through a valve seat 21 formed in the foot 10. Outwardly of the passage 20, the foot has a smooth bore 22, merging into a threaded bore 23, communicating with the recess 15.

A needle valve 24 is threaded for longitudinal 20 adjustment into the bore 23, and includes a smooth portion which is slidable in the smooth bore 22. The needle valve 24 is tapered at its inner end, so as to cooperate with the seat 21. In its outer surface, the needle valve 24 is supplied 25 with one or more longitudinal grooves 25.

The numeral 26 marks a stem, located within the body 1, centrally thereof. One end of the stem 26 is threaded into the bore 18 of the projection 16. The stem 26 carries a transverse disk 30 27, located in the inner end of the projection 16. The disk 27 may be referred to as a first disk. The stem 26 has a flat sided enlarged portion 28, located adjacent to the first disk 27 and facilitating the application of a tool whereby the stem 35 26 may be rotated and threaded into the bore 18 of the projection 16.

At one end of the stem 26 there is a second disk 29. The disk 29 is spaced from the inner surface of the end wall 6 of the body 1 and is 40 disposed opposite to the recess 30. The disks 29 and 27 taper in thickness from their centers toward their circumferences. There is a space between the peripheries of the disks 29 and 27 and the inner surface of the body 1.

At one end, the stem 26 has a passage 31, which leads through the disk 29 and communicates with the recess 30. The passage 31 includes an enlarged part 32, extended through the disk 27. The enlarged part 32 of the passage 31 has a 50 flared mouth 33 communicating with the tapered chamber 19 in the projection 16 of the foot 10. The first disk 27 is supplied with a transversely enlarged chamber 50. The second disk 29 has a plurality of openings 34 therethrough. Alter- 55
